UNITED STATES PATENT OFFICE.

WILLIAM P. GENTLEMAN, OF BEATRICE, NEBRASKA.

AIR-BRAKE.

No. 903,077.

Specification of Letters Patent.

Patented Nov. 3, 1908.

Application filed April 24, 1907. Serial No. 369,985.

To all whom it may concern:

Be it known that I, WILLIAM P. GENTLEMAN, a citizen of United States, residing at Beatrice, in the county of Gage and State of Nebraska, have invented certain new and useful Improvements in Air-Brakes, of which the following is a specification.

My invention relates to improvements in air brake systems, and has particular reference to an improved form of pressure-retaining valve; the object of the invention being to insure better regulation and control of the system, by preventing and equalizing any leakages which might ordinarily occur in the system.

A further object of my invention is to protect the equipment by furnishing means for the effective control of the air, such means serving to automatically replenish the air lost by leakage in the system and thereby do away with a constant source of danger.

With these and other objects in view, my invention consists of a pressure-retaining valve embodying certain novel features of construction, combination and arrangement of parts substantially as disclosed herein.

Figure 1, is a plan view of my invention as applied to the ordinary air brake equipment of a car. Fig. 2, is a sectional view through the regulating cylinder of my device, parts being broken away. Fig. 3, is a detail sectional view of the check valve used in connection with the cylinder. Fig. 4, is a transverse sectional view taken on the line 4—4 of Fig. 2. Fig. 5, is a similar view taken on line 5—5 of Fig. 2. Fig. 6, is a plan view of a slightly modified form of slide valve used on the engineer's valve in connection with my improvements. Fig. 7, is a plan view of the invention applied to the engine equipment of a train.

My invention is readily adaptable for use in connection with any of the ordinary air brake systems now in common use, and in the accompanying drawings I have illustrated the same as applied and in use with the well known "New York" air brake system.

Referring first to the ordinary car equipment, shown in Fig. 1: the numeral 1, designates the auxiliary reservoir, 2, the brake cylinder, 3 the triple valve, 4 the train line pipe, and 5 the conductor's valve, all of these parts being common and well known in the art so as to need no further description here. My invention consists of a cylinder 6, of con-

venient size, having the usual cylinder heads 7 and 8, and in the cylinder is arranged the piston head 9, secured upon the piston rod 10. The forward cylinder head is formed with a central raised portion or neck 11, through which the piston rod passes, and the mouth of this neck is formed with a valve seat 12, therein. A valve head 14, is carried on the outer end of the piston rod, which is adapted to engage the valve seat 12, and by-pass grooves 15, are formed in the piston rod or valve stem to form communication between the valve and the interior of the cylinder. A nipple 16, is mounted upon the cylinder head inclosing the exposed end of the valve stem, and the nipple is provided with a perforated abutment wall 17, so that the movement of the piston is limited by the valve seat and abutment wall. A pipe 18, connects the nipple with the train pipe. A second pipe 19, is secured in the forward cylinder head which by means of the connecting pipe 20, establishes communication between the brake cylinder and the regulating cylinder. A bridging pipe 21, forms an external connection between the two ends of the regulating cylinder, this pipe entering the cylinder on each side of the piston head therein, and a check valve 22, is arranged in the bridging pipe 21, so that by means of the connecting pipe 23, which is connected to the exhaust port of the triple valve (in the case of the car equipment), fluid may be admitted to the rear end of the regulating cylinder, the check valve in the bridging pipe serving to prevent admission of fluid to the front end of the cylinder and at the same time, acting as a relief valve to the front end of the cylinder.

In Fig. 7, an engine equipment is illustrated provided with my improvements. In this case, the bridging pipe 21, is connected to an extra port 24, formed in the engineer's brake valve, by means of the connecting pipe 25, the said pipe 25 entering in the seat of the engineer's valve. This extra port in the engineer's brake valve is shown more clearly in Fig. 6. The central pipe 18 in the head of the regulating cylinder is connected with the main reservoir 26, by the piping 27, and the other inlet pipe 19, is connected to the train pipe 4. This port 24 is attached at graduating valve, slide valve being pulled off port, and when reduction is made, gradually closes port. When an emergency application of air is made, it opens up port 24 to train

line. Thus port 24, is governed by the graduating valve to overcome the fluctuating in train pipe pressure.

From the foregoing, the operation of the device will be readily understood, as follows: When the brakes are in the released or running position, the auxiliary or regulating cylinder is normally empty or free of compressed air, but when an application of the brakes is made and pressure is reduced in the train pipe, the auxiliary cylinder on the car equipment is charged by means of the pipe 19, with air of the same pressure as that in the brake cylinder. This air from the brake cylinder enters the auxiliary or pressure retaining cylinder on the forward side of the piston therein, forcing the piston over and closing the piston valve, then flows through the bridging pipe past the check valve 20 therein to the rear end of the cylinder. The pressure retaining cylinder is thus charged at both ends. More or less leakage is bound to occur in the system and ordinarily this leakage would cause a reduction of pressure in the brake cylinder and a consequent loss in the braking power, but this difficulty is overcome by the use of my improvements. Assuming the auxiliary pressure retaining cylinder to be fully charged with air from the brake cylinder, and the pistons therein to be balanced with the equal pressure on both sides thereof. Now if any leakage should occur in the system, the pressure in the brake cylinder is reduced and a similar reduction is made in the pressure on the forward side of the piston in the auxiliary cylinder, since the forward end of the cylinder is connected direct to the brake cylinder. The check valve in the bridging pipe forms a stop to prevent the air from the rear side of the piston head from flowing back to the forward end thereof, so that the entrapped air in the rear compartment expands, thereby forcing the piston over and unseating the valve head on the piston rod. This forward motion of the piston thus opens communication between the train pipe and the forward end of the auxiliary cylinder, and the air then flows from the train pipe through the perforated abutment 50 wall, past the valve stem, into the forward end of the cylinder, and out through pipes 19 and 20, back to the brake cylinder. This flow continues until the pressure in the brake cylinder reaches its original dimensions 55 or slightly in excess thereof, so that the superior pressure in the forward end of the auxiliary cylinder forces the piston therein back to its former position, closing the piston rod valve, and the brakes remain set at 60 their original pressure. By this means when any accidental reduction in the pressure occurs, the brake cylinders are automatically restored to their original pressure. The same pressure is thus retained in the 65 brake cylinder at which it was applied.

When the brakes are released, the triple valve moves back, opening up exhaust port and releasing the air from the auxiliary cylinder, thereby leaving the cylinder empty or free of compressed air as it was in the beginning. The invention also provides for holding the brakes at a set pressure while recharging the auxiliary reservoirs.

The action of the engine equipment is as follows: The auxiliary cylinder is charged from the train line through pipe 19, the air passing to the rear of the piston head through the bridging pipe, and also up to the brake valve through pipe 25, to the port 24, this port being closed by the slide valve. The 75 brake valve has reservoir pressure on top of the slide valve, atmospheric pressure in body of slide valve.

When a reduction is made for setting the brakes, the exhaust port 30, is uncovered for 80 exhaust of the train pipe. After the required exhaust has taken place, the small valve 31, moves over to cover the port 30. After reduction, this small valve covers the exhaust port and the extra port 24, then if 85 any leakage occurs in the train pipe, the valve 31, moves away from the port 24, thereby reducing the pressure in the forward end of the compensating cylinder, the piston in the cylinder is forced over, thereby opening the piston rod valve, and the air from the main reservoir flows past said valve into the forward end of the cylinder and out the pipe 19 to feed up the train pipe and return all 90 valves to required position.

It will thus be seen that should any leakage occur in the system, and the pressure become reduced in the brake cylinders, it is automatically restored to the original pressure by means of the compensating action of 100 the pressure retaining cylinder.

From the foregoing description taken in connection with the drawings, it will be evident that my invention forms a valuable attachment to any air brake system, greatly increases the efficiency and reliability thereof, and further, it will be obvious that all the results herein set forth as the objects of the invention, are accomplished in a practical and satisfactory manner.

I claim:

1. The combination with an air brake system, of a compensating cylinder and piston therein for automatically controlling admission of air from the train pipe to the 110 brake cylinder, said compensating cylinder adapted to compensate for the loss due to leakage in the system.
2. The combination with an air brake cylinder, of a pressure retaining cylinder adapted to supply air at a constant pressure thereto, said pressure retaining cylinder adapted to be actuated by an accidental reduction of pressure in the brake cylinder.
3. The combination with an air brake sys- 130

tem, of a compensating cylinder connected to the exhaust from the triple valve and controlled by the pressure in the brake cylinder, to store and hold the pressure in the brake cylinder.

4. In combination with a fluid pressure brake system, auxiliary cylinders having pistons therein, valves on the piston rods of the pistons, said valves serving to open communication to the train pipe, the cylinders being connected to the brake cylinders.

5. In combination with a fluid pressure brake system, of auxiliary cylinders having pistons therein, valves on the piston rods of the pistons, said valves serving to open communication to the train pipe, the pistons being controlled by the pressure in the brake cylinder, said auxiliary cylinders being connected to an extra port on the triple valves.

20 6. In an air brake system, the combination with brake cylinder, auxiliary reservoir and train line, of a cylinder connected to the brake cylinder and train line, a piston in the cylinder, a valve in the connection to the 25 train line controlled by movements of the piston, and connections from the ends of the cylinder to the triple valve.

7. In an air brake system, the combination with brake cylinder, auxiliary reservoir and train line, of an auxiliary cylinder connected to the brake cylinder and train line, a piston in the auxiliary cylinder, a valve in the connection to the train line controlled by the movements of the piston, a bridge pipe 35 between the opposite ends of the cylinder, a check valve in said bridge pipe, and connections between said bridging pipe and the triple valve.

8. In combination with a fluid pressure 40 brake system, a cylinder and piston therein, a bridge pipe between the ends of the cylinder, an inlet to one end of the cylinder, a feed opening in one end of the cylinder, and a valve carried by the piston to close the feed 45 opening.

9. In combination with a fluid pressure brake system, a cylinder and piston therein, a bridge pipe between the ends of the cylinder connected with the triple valve, an inlet 50 in one end of the cylinder connected to the brake cylinder, and a feed valve in one end of the cylinder in communication with the train pipe.

10. In combination with a fluid pressure 55 brake system, a cylinder and piston therein, a bridge pipe between the ends of the cylinder, an inlet to one end of the cylinder, a feed opening in one end of the cylinder, and a valve carried by the piston to close the 60 feed opening, the piston being actuated by reduction of pressure due to accidental loss of pressure in the brake cylinder to open the feed valve and supply air to the brake cylinder.

11. In combination with a fluid pressure 65 brake system, a cylinder and a piston therein, a bridge pipe between the ends of the cylinder, an inlet to one end of the cylinder, a feed opening in one end of the cylinder, a valve carried by the piston to close the feed 70 opening, the inlet being connected to the train line, the feed valve to the main reservoir, and the bridge pipe to the engineer's valve.

12. In combination with an air brake system, 75 a compensating cylinder and a piston therein, an inlet to one end of the cylinder, a feed opening in one end of the cylinder, a valve carried by the piston to close the feed opening, connections between the inlet and 80 the train pipe, connections between the main reservoir and the feed opening in the cylinder, and connections between the engineer's valve and the ends of the cylinder.

13. In combination with an engineer's slide 85 valve having an extra port therein, a leakage compensating cylinder, connections between the extra port in the slide valve and the ends of the cylinder, a piston in the cylinder, a feed opening in the cylinder connected to the 90 main reservoir, a valve for the feed opening carried by the piston, and an inlet to the cylinder connected to the train pipe.

14. In combination with fluid pressure 95 braking systems, compensating cylinders provided with feed openings in communication with the train supply pipe, an automatically operated valve to control the feed openings, connections from the ends of the compensating cylinders to the triple valve, 100 and connections from the compensating cylinders to the brake cylinders.

15. In combination with fluid pressure 105 braking systems, compensating cylinders provided with feed openings in communication with the main reservoir, an automatically operated valve to control the feed openings, connections from the ends of the compensating cylinders to the engineer's brake valves, and connections from the compensating 110 cylinders to the train pipe.

16. The combination with an air brake system, of a compensating cylinder having a feed opening in communication with the main reservoir, an automatically operated 115 valve to control the feed opening, connections from the ends of the compensating cylinder to the engineer's brake valve, the said engineer's brake valve having an extra port to register with such connections, and connections from the compensating cylinder to the train pipe.

In testimony whereof I affix my signature in presence of two witnesses.

WILLIAM P. GENTLEMAN.
